UNITED STATES PATENT OFFICE.

PATRICK J. MADDEN, OF CHICAGO, ILLINOIS.

DESIGN FOR A BOWL FOR WATER-CLOSETS.

SPECIFICATION forming part of Design No. 37,180, dated October 11, 1904.

Application filed January 8, 1902. Serial No. 88,944. Term of patent 7 years.

To all whom it may concern:

Be it known that I, PATRICK J. MADDEN, a citizen of the United States, residing at Chicago, in the county of Cook and State of Illinois, have invented a new, original, and ornamental Design for a Bowl for Water-Closets, of which the following is a specification, reference being had to the accompanying drawings, which are made a part hereof, and in which—
Figures 1, 2, and 3 are respectively a side elevation, a plan, and a rear elevation, of a water-closet bowl of the new design.

What I claim as new, and desire to secure by Letters Patent, is—

The ornamental design for the bowl of a water-closet substantially as herein shown.

PATRICK J. MADDEN.
